CLAIM

I claim the ornamental design for an automatic continuous book cutting apparatus with stopping mechanism, as shown and described.

DESCRIPTION

FIG. 1 is a right side view of my new design for an automatic continuous book cutting apparatus with stopping mechanism.

FIG. 2 is a left side view of my new design for the automatic continuous book cutting apparatus.

FIG. 3 is top view of my new design for the automatic continuous book cutting apparatus.

FIG. 4 is a bottom view of my new design for the automatic continuous book cutting apparatus.

FIG. 5 is a perspective view from the right side, rear and bottom of my new design for the automatic continuous book cutting apparatus; and,

FIG. 6 is a perspective view from the right side, front and bottom of my new design for the automatic continuous book cutting apparatus.
